UNITED STATES PATENT OFFICE.

FRANK ACKERMAN, OF ST. LOUIS, MISSOURI, ASSIGNOR TO CURTIS MANUFACTURING COMPANY, OF WELLSTON, MISSOURI, A CORPORATION OF MISSOURI.

STOP-SWITCHING APPARATUS FOR ENGINE-DRIVEN COMPRESSORS.

Application filed June 12, 1926. Serial No. 115,608.

This invention relates to a stopping apparatus of novel construction that is adapted to be used for automatically stopping an engine used for driving a compressor when the pressure of the medium in the storage tank that is connected with the compressor reaches a predetermined degree.

One object of my invention is to provide a stopping apparatus of the kind referred to that is inexpensive to construct and reliable in operation.

Another object is to provide an automatic stopping apparatus for an engine driven compressor which is equipped with a signal that operates automatically when the pressure in the storage tank drops below a predetermined degree, thus notifying the operator in charge of the compressor that the engine should be started so as to raise the pressure in the storage tank.

Figure 1 is a side elevational view of an engine driven air compressor equipped with a stopping apparatus constructed in accordance with my invention.

25 Figure 2 is an enlarged side elevational view of said apparatus; and

Figure 3 is a vertical sectional view, taken on the line 3—3 of Figure 2, looking in the direction indicated by the arrows.

30 In the drawings A designates an internal combustion engine, B designates a compressor that is driven by said engine and C designates a storage tank for receiving the medium compressed by the compressor. My improved apparatus is used for automatically stopping the engine A when a predetermined maximum pressure is reached in the storage tank C and for operating a signal D whenever the pressure in the storage tank drops below a

40 predetermined minimum pressure. The apparatus can be constructed in various ways and it can be used in connection with various types and kinds of engines. I have herein illustrated the apparatus as being designed for use with an internal combustion engine equipped with an electrical ignition mechanism, and when constructed in this manner, the stopping of the engine is effected by grounding the ignition circuit.

45 The apparatus comprises a pressure operated member 1, preferably a flexible diaphragm, arranged so that when a certain maximum pressure is reached in the storage tank C, said member 1 will cause a change to 50 take place in the condition of the ignition

mechanism of the engine A that results in the stopping of said engine. When the pressure in the storage tank C drops to a certain minimum pressure, the signal D operates automatically, thus notifying the operator that the engine should be started so as to raise the pressure in the storage tank. In the preferred form of my invention, as herein illustrated, a grounding device consisting of a pivotally mounted lever 2 is normally held in an inactive position by means of a latch 3, and when the predetermined maximum pressure is reached, the pressure-operated member 1 disengages said latch 3 from the grounding device 2, thereby permitting a spring 4 to move 55 said grounding device into engagement with a contact 5 and cause the ignition mechanism of the engine A to be grounded. The diaphragm 1 is arranged so that the pressure in the storage tank C is normally exerted 60 on said diaphragm in a direction tending to flex it upwardly, and a spring-pressed plunger 6 is arranged above the diaphragm so as to resist the upward movement of the diaphragm, the actuating spring 7 of the plunger 6 being combined with a nut 8 that is adapted 65 to be adjusted so as to vary the tension of said spring. The diaphragm 1 is clamped between a base plate 9 and a member 10 that houses the plunger 6, and the latch 3, previously referred to, is pivotally mounted on a pin 11 carried by a bracket 12 on the housing 10. The grounding lever 2 is pivotally mounted on a supporting standard 13, and the contact 70 5 with which the grounding lever 2 co-operates is carried by a piece 14 of fibre or other suitable insulating material, as shown in Figure 2.

75 Any suitable type of signal D may be used, either an audible or visual signal, but I prefer to use an audible signal consisting of a bell arranged in an electric circuit provided with a switch that is held in its open position, so long as the pressure in the storage tank C exceeds the predetermined minimum pressure, and which moves automatically into its closed position whenever the pressure in the tank C reaches or drops below the predetermined minimum pressure. The switch that governs the signal circuit comprises a movable switch 80 member herein illustrated as a lever 15 pivotally mounted on the pin 11 and provided with a portion that is interposed between the underside of the latch 3 and the upper end of the plunger 6, said switch member being arranged 85

90 95 100 105 110

above an adjustable contact 16 in the signal circuit carried by a binding post 17 on the insulator 14. The contact 16 is adapted to be set in such a position that the diaphragm 1 operating in conjunction with the plunger 6 will hold the switch member 15 out of engagement with said contact 16 when the pressure in the tank C is above the predetermined minimum pressure, and when the pressure in 10 said tank drops below said minimum, the switch member 15 will be moved downwardly into engagement with the contact 16 by a spring, weight or other suitable means, herein illustrated as a weighted lever 18, pivotally 15 mounted on the pin 11 and arranged so that it normally exerts pressure on the switch member 15 in a direction tending to move said member towards the contact 16. In the form 20 of my invention herein illustrated the switch member 15 is channel-shaped in cross section and is arranged so that it embraces the latch 3, and the weighted lever 18 is provided with a bifurcated portion 18^a that straddles the upper end portion of the bracket 12. It is ob- 25 vious, however, that said elements could be constructed in various other ways without departing from the spirit of my invention.

To install the apparatus the base plate 9 is first connected to the top side of the storage 30 tank C by means of a tubular, screw-threaded connection 19 arranged in alignment with a hole in the base plate 9 which permits the pressure in the tank C to be exerted on the diaphragm 1. A wire *w* that leads from the 35 spark plug or magneto of the ignition mechanism of the engine A is then connected to the contact 5 on the insulator 14 and a ground wire *y* which leads from the frame or some other metallic part of the engine A is then connected to the bracket 12 on the housing 10 by means of a binding screw 20. The signal 40 circuit is then connected with the switch that controls the signal D by attaching the wire *t* of the signal circuit to the binding screw 20 on the bracket 12 and attaching the wire *w* of the signal circuit to the binding post 17 so as to establish electrical connection between said wire *w* and the contact 16. In adjusting the apparatus the 45 weighted lever 18 is arranged in the position shown in full lines in Figure 2 and the latch 3 is arranged in engagement with the upper end of the grounding lever 2 so as to hold said grounding lever out of engagement with the contact 5. After the engine A has been 50 started so as to raise the pressure in the storage tank C, the nut 8 that governs the tension of the spring 7 is backed off slowly so as to permit the plunger 6 to move upwardly and exert upward pressure on the switch member 15 that 55 embraces the latch 3, said nut 8 being backed off until the predetermined maximum pressure is reached, whereupon the latch 3 will move upwardly out of engagement with the grounding member 2, due to the upward 60

pressure exerted on said latch by the switch member 15, the plunger 6 and the diaphragm 1. As soon as the latch 3 is disengaged from the grounding lever 2, said lever will move under the influence of the spring 4 into engagement with the contact 5, thereby grounding the ignition mechanism of the engine A and causing said engine to stop. The pressure in the storage tank C is then reduced and at the same time the contact 16 is backed off or 70 screwed downwardly. When the pressure in the storage tank is reached that is to constitute the minimum pressure, the contact 16 is locked in adjusted position, so that it will co-operate with the switch member 15 to close 75 the signal circuit whenever the pressure in the storage tank thereafter drops to or below the minimum pressure.

After being adjusted in the manner above described the engine A can be set in operation 80 so as to raise the pressure in the storage tank C, and when the maximum pressure is reached the latch 3 will be tripped automatically, thereby causing the engine to stop. The signal D remains inactive so long as the pressure 85 in the tank C exceeds the minimum pressure, but whenever the pressure drops to or below minimum, the switch member 15 will engage the contact 16 and thus close the signal circuit. If it is desired to manually stop the 90 engine A, this can be effected by swinging the lever 18 to the left into the position shown in broken lines in Figure 2, so as to cause said lever to swing the switch member 15 upwardly, and thus cause the latch 3 to be disengaged 95 from the grounding lever 2, which immediately moves into engagement with the contact 5, thus grounding the ignition mechanism of the engine. At night or at other 100 times when it is not necessary to maintain a 105 certain approximate pressure in the storage tank C, the lever 18 is arranged in the position shown in broken lines in Figure 2, so as to prevent the signal circuit being closed should the pressure in the storage tank drop below 110 the minimum, the bracket 12 on the housing 10 being provided with a supporting lug 21 on which the lever 18 rests at such times.

A stopping apparatus of the construction above described is inexpensive to construct, it is easy to install and adjust and it is of such simple design that it is absolutely reliable for the use for which it is intended.

Having thus described my invention, what I claim as new and desire to secure by Letters 115 Patent is:

1. An apparatus for the purpose described, comprising a base plate, a spring-actuated, pivotally mounted grounding lever carried by said base plate, a latch for holding said grounding lever in an inactive position, a diaphragm on said base plate adapted to be flexed in one direction by the pressure in a storage tank, a spring-actuated plunger for resisting 120 movement of said diaphragm in one direction, 125

said plunger being adapted to be actuated by said diaphragm to trip said latch, means for varying the tension of the spring of said plunger, a switch comprising a switch member arranged between said latch and a contact in the switch circuit, and a means capable of exerting pressure on said switch member in a direction tending to move it towards its co-operating contact when said latch is disengaged from said grounding lever.

2. An apparatus for the purpose described, comprising a base plate adapted to be connected to a storage tank, a diaphragm on said base plate arranged so that it will be flexed in one direction by the pressure in said tank, a spring-actuated plunger for flexing the diaphragm in an opposite direction, a spring-actuated grounding lever carried by said base plate, a latch for holding said grounding lever in an inactive condition, adapted to be tripped by said plunger, an insulator provided with a contact, a pivotally mounted switch member arranged between said latch and the upper end of said plunger, and a pivotally mounted, weighted lever that normally exerts pressure on said switch member in a direction tending to hold it in engagement with said plunger whereby movement of said plunger under the influence of its spring after said latch has been tripped causes said switch member to engage said contact.

3. An apparatus for the purpose described, comprising an automatically operating stopping member, a pivotally mounted latch for holding said stopping member in an inactive position, a diaphragm adapted to be flexed in one direction by the pressure in a storage tank, a spring-actuated plunger for tripping said latch arranged so as to resist movement of said diaphragm in one direction, and a switch comprising a switch member interposed between said latch and said plunger whereby movement of said diaphragm resulting from a diminution of the pressure in the storage tank causes said switch member to become operative when the pressure in the storage tank reaches a predetermined minimum.

4. An apparatus for the purpose described, comprising an automatically operating stopping member, a pivotally mounted latch for holding said stopping member in an inactive position, a diaphragm adapted to be flexed in one direction by the pressure in a storage

tank, a spring-actuated plunger for tripping said latch arranged so as to resist movement of said diaphragm in one direction, a switch comprising a switch member interposed between said latch and said plunger whereby movement of said diaphragm resulting from a diminution of the pressure in the storage tank causes said switch member to become operative when the pressure in the storage tank reaches a predetermined minimum, and a means that is adapted to be actuated to hold said switch member in engagement with said plunger or out of engagement with said plunger.

5. An apparatus for the purpose described, comprising a base plate adapted to be connected to a storage tank, a diaphragm on said base plate that is adapted to be flexed in one direction by the pressure in said tank, a spring-actuated plunger arranged above said diaphragm for flexing the diaphragm in the opposite direction, an automatically-operating stopping member, a pivotally mounted latch for holding said stopping member in an inactive position arranged above said plunger and adapted to be actuated by same to release the stopping member, and a pivotally mounted switch member interposed between the underside of said latch and the upper end of said plunger, for the purpose described.

6. An apparatus for the purpose described, comprising a base plate adapted to be connected to a storage tank, a diaphragm on said base plate that is adapted to be flexed in one direction by the pressure in said tank, a spring-actuated plunger arranged above said diaphragm for flexing the diaphragm in the opposite direction, an automatically-operating stopping member, a pivotally mounted latch for holding said stopping member in an inactive position arranged above said plunger and adapted to be actuated by same to release the stopping member, a pivotally mounted switch member interposed between the underside of said latch and the upper end of said plunger, for the purpose described, and a pivotally mounted, weighted lever adapted to be arranged in one position wherein it holds said switch member in engagement with the upper end of said plunger and in a different position wherein it holds said switch member in an inactive position.

FRANK ACKERMAN.
